UNITED STATES PATENT OFFICE.

LEONARD D. SOUBIER, OF TOLEDO, OHIO, ASSIGNOR TO THE OWENS BOTTLE COMPANY,
OF TOLEDO, OHIO, A CORPORATION OF OHIO.

MECHANISM FOR TRANSFERRING WARE FROM LEERS.

Application filed December 15, 1922. Serial No. 607,121.

To all whom it may concern:

Be it known that I, LEONARD D. SOUBIER, a citizen of the United States, residing at Toledo, in the county of Lucas and State of Ohio, have invented new and useful Improvements in Mechanism for Transferring Ware from Leers, of which the following is a specification.

My invention relates to leers for annealing 10 glass articles, and automatic mechanism for handling the articles at the delivery end of the leer. More particularly, the invention relates to automatic means for transferring bottles or other articles from the leer pans 15 on which they are held in inverted position, placing them in upright position on a horizontal conveyor and carrying them away from the leer.

An object of the invention is to provide a 20 practical form of mechanism for automatically receiving and conveying the ware from the leer to selecting tables or a convenient place for inspecting, sorting and packing the ware. In this manner there is avoided 25 the necessity of selectors working at the end of the leer under the crowded, overheated and inconvenient conditions which usually prevail with present methods, these adverse conditions being especially pronounced 30 where the output of the leer is large.

Other objects of the invention will appear hereinafter.

In the accompanying drawings:

Figure 1 is an elevation view of the delivery and of the leer, parts being broken away.

Figure 2 is a side elevation of the same, with mechanism for transferring the bottles from a leer pan to a horizontal conveyor.

Figure 3 is a detail showing the method of 40 placing the bottles on the horizontal conveyor.

Figure 4 is an elevation view of the horizontal conveyor and associated mechanism.

Figure 5 is a plan view of the same.

Figure 6 is a detail of a carrier on which 45 the bottles are transferred from the leer pan to the horizontal conveyor.

Figure 7 is a detail view of the mechanism for discharging the bottles from the leer 50 pans and transferring the pans from the leer to a conveyor outside the leer.

The present invention is herein shown in connection with a leer of the type disclosed in the patent to Michael J. Owens, Number 1,117,433, November 17, 1914. In this

type of leer the leer conveyor comprises a series of pans or ware holders which travel through the leer from the receiving to the discharge end of the leer, each pan extending transversely of the leer and provided with a row of sockets or holes to support bottles or the like in an upright inverted position. Each said pan when it reaches the discharge end of the leer, is automatically shifted in the direction of its length to a position at one side of the leer, is advanced to a receiving position, receives a fresh supply of articles to be annealed and is returned to the receiving end of the leer. This general method of operation is carried out in connection with the present invention.

Referring now to the accompanying drawings:

The leer pans or holders 10 extend transversely of the leer and are placed side by side one in advance of another, as indicated in Figure 2. Each said holder is provided with a row of sockets or holes 11 shaped to receive the necks of bottles 12 or other glass articles and hold them spaced apart in an upright inverted position. The leer pans 10 adjacent the discharge end of the leer are supported on beams or supporting bars 13 extending lengthwise of the leer. The pans are advanced step by step by means of shifting supports or carriers 14 (Fig. 1) actuated by a cam 15 operating through a lever 16 and links 17. This operating mechanism may be of the usual or standard construction.

The leer pans as they reach the discharge end of the leer are received by a transfer mechanism which transfers the pans to a carrier 19 and transfers the bottles to holders 35 which in turn transfer them to a horizontal conveyor 42. This transfer mechanism comprises a shaft 20 extending transversely of the leer, arms 22 fixed to and extending radially from the shaft and holders 23 at the outer ends of said arms. Said holders may be in the form of angle bars shaped to receive and hold the leer pans 10. The transfer device, as shown, comprises three of said holders 23 equally spaced around the shaft 20 and arranged to be brought successively in alignment with the leer pans.

The transfer device is given a step by step rotation by means of reciprocating slide blocks 24 working in stationary guides 25

and actuated by cams 26 on which run rolls 27 carried by said slide blocks. The cams 26 are fixed to a shaft 9 driven through worm gearing 8. The motion of said slide blocks 24 is transmitted through levers 28 fulcrumed at 29 and connected through links 31 to rock arms 32 loose on the shaft 20. Said arms 32 operate through a pawl and ratchet 33 to rotate the transfer device 10 step by step. This operation is in timed relation to the step by step feed of the leer pans, so as to pick up and transfer a leer pan and its ware after each advance of the leer pans in the leer. 15 Each operation of the transfer device causes a pair of holders 23 to pick up the outermost leer pan in the leer and swing it from position *a* (Fig. 7) to position *b*. The leer pan is thus partially inverted and 20 places the bottles carried thereby on an inclined platform 34. The bottles slide down this platform onto holders 35 on the endless carrier chains 18. The bottles will ordinarily be released from the leer pans and 25 slide by gravity down the platform 34 without additional assistance. Sometimes, however, there is a tendency for the bottles or other ware to stick in the leer pans, and in order to insure their release, a positive 30 means is provided comprising a bar 36 carried by rock arms 37 on a rock shaft 38 having connection through links 39 with slide blocks 40 in the path of the levers 28. When the levers 28 operate to transfer a 35 leer pan to position *b*, the bar 36 through the connections just described, is swung down to the position shown in Figure 7 and in dotted lines in Figure 2, thereby striking and releasing from the leer pan any bottles 40 which have not already been released, and also giving them a forward impulse or start down the platform 34.

The conveyor comprising the holders 35 and chains 18, is preferably given a step by 45 step movement in timed relation to the movements of the transfer device, so that a holder 35 is always in position at the lower end of the platform 34 when required to receive the row of bottles discharged from the 50 leer pan. This step-by-step movement is effected by means of a pawl and ratchet device 7 (Fig. 2) actuated by the lever 28 connected thereto through a link 6.

The holders 35 discharge the bottles on 55 the horizontal conveyor 42. For this purpose, they are provided with lugs 43 pivoted to the conveyor chains, and are also provided with arms 44 carrying cam-engaging rolls or studs 45 which run on stationary cams 46 and 47. The cam 46 is so shaped that it will guide the holder 35 and cause it to deposit the bottles on the horizontal conveyor 42, as indicated in Figure 60 3. In this connection, it will be noted that, as shown in Figure 6, the bottoms of the

bottles protrude beyond the edge of the holder 35. This insures the bottles being arrested by and pushed onto the conveyor. In order to prevent the bottles from being tipped over as they are placed on the conveyor, a guard 48 is provided. This guard is adjustably mounted on stationary brackets 49 and is held in adjusted position by a set screw 50.

The horizontal conveyor 42 extends across the front end of the leer and for some distance beyond the leer at one side thereof, as shown in Figures 4 and 5, so that the bottles or other articles are carried to selector tables or within convenient reach of the selectors at the stations 52. The selectors seated at these stations may take the bottles from the conveyor and inspect them in the usual way, discarding the defective ware and packing the perfect ware. An inclined stationary guide 53 (Fig. 5) is arranged to guide the bottles from the edge to the center of the conveyor. Each row of bottles is carried by the conveyor to a position at one side of the leer before the next row of bottles is placed thereon.

As each leer pan is moved from position *a* (Fig. 7) to position *b*, the pan in advance thereof is at the same time moved from position *b* to a position *c*. The holder 23 by the time it reaches position *c* has been inverted, so that it permits the leer pan to drop therefrom and slide down an inclined guideway 54 onto a conveyor 55. Figure 7 shows, in broken lines, the leer pan in successive positions assumed as it slides down the incline 54. A guard 56 prevents the leer pans from dropping out of the holders 23 before they have reached the position *c*. It will be noted that each leer pan during its transfer from position *a* to the conveyor 55, is given a complete rotation about its own axis, so that it is again right side up when it reaches said conveyor. The pan is now returned to position to receive a new supply of bottles and again introduced into the leer by mechanism such as disclosed in the Owens patent above referred to, or other approved mechanism, which need not be here described.

Modification may be resorted to within the spirit and scope of my invention.

What I claim is:

1. The combination of a leer, leer pans therein comprising means to hold articles in upright position on the pans, a transfer device at the discharge end of the leer, and means operable to actuate said transfer device and cause it to transfer the leer pans from the discharge end of the leer to a position external to the leer and discharge the articles from the leer pans.

2. The combination of a leer, leer pans therein including means for holding articles, a conveyor located outside of the leer, a

- transfer device, and means to actuate said device and cause it to automatically transfer the leer pans from the leer to the conveyor and discharge said articles from the pans.
- 5 3. The combination of a leer, leer pans therein and by which articles are carried, a conveyor located outside of the leer, a transfer device, and means operable to actuate said device for transferring the pans from 10 the leer and placing the articles in an upright position on said conveyor.
4. The combination of a leer, conveying mechanism within the leer comprising holders for holding articles in rows extending 15 transversely of the leer, a transfer device, and automatic means to actuate said device and thereby transfer said articles one row at a time to a position outside of the leer and away from the holder.
- 20 5. The combination of a leer, conveying mechanism within the leer comprising holders for holding articles in rows extending transversely of the leer, a conveyor outside of the leer, a transfer device, and means to 25 actuate said device and transfer said holders bodily to a position outside the leer and thereby transfer articles a row at a time from the leer to a discharging position, and means to discharge said articles from the 30 holders to said conveyor.
6. The combination of a leer, conveying mechanism within the leer, leer pans loosely mounted thereon and adapted for holding articles in rows extending transversely of 35 the leer, a conveyor outside of the leer, and means operable automatically to transfer said articles a row at a time from the leer pans to said conveyor and place them in an upright position on the conveyor.
- 40 7. The combination of a leer, conveying mechanism within the leer, leer pans mounted thereon and adapted for holding articles in rows extending transversely of the leer, a conveyor outside of the leer, and means 45 operable to transfer said articles a row at a time from the leer to said conveyor while supported in the leer pans and place them in an upright position on the conveyor in a row extending lengthwise of the conveyor, 50 said conveyor operable to convey each row of articles thereon away from the leer before the next succeeding row is placed thereon.
8. The combination of a leer, conveying 55 mechanism within the leer, leer pans loosely mounted thereon and adapted for holding articles in rows extending transversely of the leer, a conveyor extending transversely of the leer, and means operable to transfer 60 the leer pans from the leer to a position external to said leer and simultaneously discharge the articles therefrom a row at a time, and place them on the conveyor, said conveyor being arranged to carry the articles 65 to a position at one side of the leer.
9. The combination of a leer, conveying mechanism within the leer, leer pans adapted for holding articles in rows extending transversely of the leer, a conveyor outside of the leer, automatic means to transfer said 70 articles a row at a time from the pans to said conveyor, said transfer means comprising holders each adapted to receive a row of said articles, and endless chains connecting said holders and operable to carry each 75 holder from an article receiving position to a position to discharge the articles and cause them to be placed on the conveyor.
10. The combination of a leer, a leer conveyor therein, article holders loosely mounted thereon, each comprising means for holding a plurality of articles, means for feeding said holders through the leer, a transfer device, and means to actuate said device to move the said holders from an upright 80 position on the leer to an inclined discharging position external of the leer and cause the articles to be discharged from said 85 holders.
11. The combination of a leer, a leer conveyor therein, article holders loosely mounted thereon, each comprising means for holding a plurality of articles, means for feeding said holders through the leer, and a transfer device operable to transfer said 90 holders bodily from their position on the leer conveyor to a discharging position and cause the articles to be discharged from said 95 holders.
12. The combination of a leer, leer pans 100 therein each having sockets to receive articles and hold them in an upright position, transfer mechanism comprising a holder to engage a leer pan, and means to actuate said holder and swing the leer pan to a discharging position, permitting the articles to be 105 discharged therefrom.
13. The combination of a leer, leer pans 110 therein, each having sockets to receive articles and hold them in an upright position, transfer mechanism comprising a holder to engage a leer pan, and means to actuate said holder and move the leer pan to a position in which the articles carried thereby are in a downwardly inclined position, permitting 115 them to be discharged from the leer pan.
14. The combination of a leer, leer pans 120 therein, each having sockets to receive articles and hold them in an upright position, transfer mechanism comprising a holder to engage a leer pan, means to actuate said holder and move the leer pan to a position in which the articles carried thereby are in a downwardly inclined position, permitting 125 them to be discharged from the leer pan, and means to receive said articles as they are discharged from the leer pan and place them in an upright position.
15. The combination of a leer, leer pans 130 therein, each provided with sockets to re-

- ceive a row of bottles and hold them upright in an inverted position, a transfer device comprising holders each formed to support a leer pan, means to feed the leer pans forward through the leer, means to rotate said transfer device and cause said holders to successively engage the leer pans and swing each pan to a position in which the bottles carried thereby are downwardly inclined to permit the discharge of the bottles by gravity, means to receive the discharged bottles, and means to positively disengage from the leer pan any articles that are not discharged therefrom by gravity.
16. The combination of a leer, leer pans therein, each provided with sockets to receive a row of bottles and hold them upright in an inverted position, a transfer device comprising holders each formed to support a leer pan, means to feed the leer pans forward through the leer, means to rotate said transfer device and cause said holders to successively engage the leer pans and swing each pan to a position in which the bottles carried thereby are downwardly inclined to permit the discharge of the bottles by gravity, means to receive the discharged bottles, means to positively disengage from the leer pan any articles that are not discharged therefrom by gravity, holders positioned and arranged to receive each row of articles as they are discharged from the leer pan, a support, and means to actuate said holders and cause them to place the articles in an upright position on said support.
17. The combination of a leer, a traveling leer conveyor therein, article holders mounted on the conveyor and carried thereby through the leer, automatic means for moving the holders bodily away from the conveyor, and means for then discharging the articles from the holders.
18. The combination of a leer, conveying means therein, article holders supported on said conveying means and by which articles are carried through the leer, automatic means to transfer the holders which the articles thereon away from said conveying means and away from the discharge end of the leer, and means cooperating with said holders to place the articles in upright position on a support outside the leer.
19. The combination of a leer, leer pans therein including means to hold articles in upright position on the pans, a transfer device, automatic means to actuate said device to transfer the pans to discharging position, and means to discharge the articles from said pans.
20. The combination of a leer, leer pans therein including means to hold articles in upright position on the pans, a transfer device, automatic means to actuate said device to transfer the pans to a discharging position, means to discharge the articles from said pans, and a second transfer device arranged to receive the articles as discharged from the pans.
21. The combination of a leer, article supporting leer pans therein, a transfer device, means to actuate said device to transfer the pans to a discharging position, means to discharge the articles from said pans, a second transfer device, a conveyor extending transversely of the leer, and means to actuate said second transfer device to transfer the articles from the leer pans to said conveyor.
22. The combination of a leer, a conveyor adapted to convey article supporting leer pans within the leer, traveling a pan-receiving conveyor located externally of the leer, a transfer device, and automatic means to actuate said device to transfer the pans from the leer conveyor to the pan conveyor.
23. The combination of a leer, a conveyor adapted to convey article supporting leer pans within the leer, traveling a pan-receiving conveyor located externally of the leer, a transfer device, automatic means to actuate said device to transfer the pans from the leer conveyor to the pan conveyor, and means operable to discharge the articles from said leer pans during their passage from one conveyor to the other.
- Signed at Toledo, in the county of Lucas and State of Ohio, this 13th day of December, 1922.
- LEONARD D. SOUBIER.
